UNITED STATES PATENT OFFICE.

WALTER E. IRVING, OF GLENBROOK, CONNECTICUT.

SUPPORT FOR GRATINGS.

1,327,711.

Specification of Letters Patent. Patented Jan. 13, 1920.

Application filed July 3, 1919. Serial No. 308,540.

To all whom it may concern:

Be it known that I, WALTER E. IRVING, a citizen of the United States of America, residing at Glenbrook, county of Fairfield, 5 State of Connecticut, have invented certain new and useful Improvements in Supports for Gratings, of which the following is a specification.

My invention relates to supports for grating, such, for instance, as are used to cover ventilating openings over subways, etc. Heretofore these gratings have usually been supported in a rectangular angle-iron frame, the horizontal flanges of the angle-irons projecting inward and forming a step on which the ends of the grating rested. The ends of the grating bars extending across this step to the vertical flange of the angle-iron formed a series of pockets in which dirt and decayed 20 matter collected, and from which this material could not be easily cleaned out. Such collected matter holds moisture and this rapidly rusts out the grating and support. My invention overcomes these difficulties by 25 providing a self-cleaning support for the grating.

The best form of apparatus embodying my invention at present known to me is illustrated in the accompanying sheet of 30 drawing, in which:

Figure 1 is a detail vertical section on line 1—1 of Fig. 2 of one of the supports and also shows a part of the supported grating, and

Fig. 2 is a plan view of the grating and 35 two supports but with parts broken away.

Throughout the drawings like reference characters indicate like parts. 1, represents a mass of concrete which usually surrounds the opening in which the grating is placed. 40 In this is embedded the horizontal flange 3, of an angle iron, the vertical flange 2, of which forms a facing and retaining wall for the upper portion of the concrete. Preferably this angle-iron is still more securely 45 fastened in the concrete by a series of bent anchors, 4, 4, fastened to flange 3, and extending farther into the concrete. The structure so far described forms an anchorage for the grating supports which anchorage has a 50 smooth vertical face against which the ends of the grating bars may abut.

To this anchorage are fastened a plurality of metal strips bent to form knees 5, 5. The upper portions of each knee-forming 55 strip lies against the vertical flange 2, of the

angle-iron forming the anchorage face, and is fastened thereto by rivets 6, 6. The lower portion of the strips is bent outward, downward and backward to form the knee, its lower end preferably abutting against the 60 anchorage face to obtain additional support.

7, 7, are horizontal bars fastened to knees 6, 6, by rivets 8, 8, and 9 is the grating, the bars of which rest on the upper surfaces of 65 bars 7, 7. As shown the upper portions of some of the knee-forming strips extend into the spaces between the ends of the grating bars and serve as stops or cleats preventing sidewise movement of the grating on 70 bars 7, 7.

The bars 7, 7, being offset from the anchorage wall or face by knees 6, 6, there are open spaces under the grating ends adjacent the anchorage through which dirt and refuse 75 may pass. Any dirt striking knees 6, 6, slides down their inclined upper surfaces, and any small amounts on the narrow upper edges of bars 7, 7, are soon blown off.

Having described my invention, I claim: 80

1. A support for gratings comprising in combination an anchorage, a plurality of horizontally projecting members mounted on said anchorage and a horizontal bar fastened to said projecting members offset from 85 the anchorage and having its upper edge adapted to serve as a support for the ends of the bars of a superposed grating.

2. A structure such as set forth in claim 1, in which the horizontally projecting members extend upward and are adapted to enter between some of the bars of the superposed grating, whereby side movement of the said grating on the horizontal bar is prevented. 90

3. A structure such as set forth in claim 1 95 in which the horizontally projecting members extend upward and are adapted to enter between some of the bars of the superposed grating and have their upper surfaces sloping downward and outward from the anchorage, whereby side movement of the said grating on the horizontal bar is prevented. 100

4. A support for gratings comprising in combination an anchorage having a vertical face, a plurality of short metal bars bent to 105 form knees, means for fastening the upper ends of these knees to the anchorage at regularly spaced intervals and a horizontal bar fastened to the projecting portions of the knees, whereby there is formed a support for 110

a superposed grating which support is offset from the anchorage.

5. An end support for a grating comprising in combination a body of concrete, an angle iron having a horizontal flange buried in said concrete and a vertical flange forming a vertical retaining wall for the upper portion of the concrete mass, projecting members fastened to the outer face of said vertical flange and a horizontal bar fastened 10 to said projecting portions and thereby off-

set from the anchorage formed by the concrete mass and the embedded angle iron.

6. A structure such as set forth in claim 5, combined with bent anchor strips fastened 15 to the horizontal flange of the angle iron and still further embedded in the concrete.

WALTER E. IRVING.
